SLING STRAP CONNECTING DEVICE

Oscar F. Mossberg, New Haven, Conn., assignor
to O. F. Mossberg and Sons, Inc., New Haven,
Conn., a corporation of Connecticut

Application September 3, 1936, Serial No. 99,251

10 Claims. (Cl. 42—85)

This invention relates to sling strap connecting devices and more particularly to improvements in sling strap swivels and in the means to connect the same to a gun or the like article.

5 Sling straps for guns are generally used for carrying them hung across the back of, and from, the user's shoulder, and for steadyng the gun during its use in shooting. The ends of these straps are generally secured to the gun by swivels, 10 disposed at spaced apart points, one being disposed adjacent the butt end and the other disposed intermediate this end and the muzzle end of the gun. It is desirable that provision be made to shorten the distance between these 15 points, preferably by moving the intermediate connection rearwardly toward the butt end, to compensate for differences in stature of different users so that the gun will be comfortably and properly positioned and balanced while being so carried. It is also desirable, when the gun is to 20 be used for shooting to be able to quickly and readily change the degree of looseness of the strap. Due to the present form of strap connecting devices this requires the lengthening of 25 the strap between its holding swivels by unbuckling its ends and adjusting its length to suit, which is inconvenient and time consuming.

One of the principal objects of this invention is to provide means to adjustably connect a sling 30 strap to a gun or the like, whereby desired changes in length and degree of looseness of the strap between the points of its connection with the gun, may be quickly and readily made.

Another object is to provide means to selectively position and connect one of the sling strap 35 swivels to the gun or like article in any one of a plurality of positions to obtain the above mentioned desiderata.

Still another object is to provide means to 40 tachably connect a sling strap swivel to a member connectable to a gun part and which may include means to releasably lock the same to said member.

A further object is to provide means in the 45 structure of a sling strap swivel for a gun or like article to sustain another part of the swivel in position, to locate the swivel in operable position in respect to the gun, and to releasably lock the swivel to the gun.

50 It is also an object of this invention to provide a sling strap connecting device of generally improved construction, whereby the device will be simple, durable and inexpensive in construction, as well as convenient, practical, serviceable 55 and efficient in its use.

With the foregoing and other objects in view, which will appear as the description proceeds, the invention resides in the combination and arrangement of parts, and in the details of construction hereinafter described and claimed. 5

The preferred embodiment of the invention is illustrated in the accompanying drawing, in which like reference characters indicate similar parts, and wherein;

Figure 1 is a side view of a gun having a sling 10 strap secured thereto by a device embodying the features and principles of this invention;

Figure 2 is an enlarged bottom plan view of a portion of the gun and the other parts shown in Figure 1; 15

Figure 3 is an enlarged sectional view on line 3—3 of Figure 2;

Figure 4 is an enlarged sectional view on line 4—4 of Figure 2;

Figure 5 is a sectional view on line 5—5 of 20 Figure 3;

Figure 6 is an enlarged sectional view somewhat similar to Figure 3, taken through a sling strap swivel, and showing by the use of dotted lines the operation and position of the several 25 parts thereof when removing it from the gun;

Figure 7 is a plan view of the parts shown in Figure 6;

Figure 8 is an enlarged sectional view on line 30 6—6 of Figure 2, and

Figure 9 is a detail view of a spring part of the device.

The arrangement and structure of the parts whereby the device of this invention may be quickly and readily connected to a gun or like 35 article to obtain the advantages and results contemplated and particularly whereby one of the sling strap swivels 10 or 11 may be selectively positioned in any one of a plurality of positions, disposed lengthwise of the gun 12, comprises a 40 bar or plate 13 securable to the gun 12 by means of screws 14 and co-operating means between the plate 13 and one of the strap swivels, in this instance, swivel 10. The plate 13 is preferably disposed, as herein shown, in a recess 15 formed in and adjacent to one end of the gun stock 16. A bracket 17 secured adjacent the other end of the gun stock 16 by screws 18, is provided to which the swivel 11 may be releasably secured by similar co-operating means between this 45 bracket and the swivel 11.

The co-operating means between the swivels 10 and 11 and the plate 13 and bracket 17 respectively, comprises a tongue 19 on one, herein shown on the swivels, and a slot 20 in the other, herein 55

shown, one slot in the bracket 17, and a plurality of slots, spaced apart lengthwise of the gun, in plate 13. Each of the slots 20 is formed with a central circular opening 21 with extensions 22 at 5 both sides thereof which are narrower in dimension than the diameter of the opening 21. The tongues 19 are elongated to easily pass through the slots 20, when disposed in alignment therewith, and be disposed beneath the plate 13. When 10 so disposed the tongues 19 are turned, by rotation of the respective swivel, at right angles to their aligned position with the slots 20, whereby the ends thereof overlap the plate 13 at each side of the central opening 21, thereby preventing removal of the tongues from the plate. A counterbore 23 is formed in the gun stock 16, concentric to each of the spaced apart openings 21 in the plate 13, to permit the turning of the tongue 19 and the bracket 17 is struck outwardly, as at 24, 15 for the same purpose.

The tongue 19, of each swivel 10, 11, is spaced from a cylindrical body portion 25 of each, an amount substantially equal to the thickness of the plate 13, or bracket 17, and is connected thereto by a cylindrical neck 26. The diameter of the neck 26 is slightly less than the diameter of the opening 21, to permit its insertion and rotation therein. By this arrangement the neck 26 forms 20 centralizing means for the tongue 19 in respect to the slot 20, and a trunnion, fitting the opening 21 which acts as a bearing for the respective swivel. An elongated loop or bail 27, having its spaced apart ends 28 and 29 opposed and inserted in a suitable transverse bore 30 provided in the 25 body portion 25, is provided, to support the sling strap 31 in the usual manner.

In order to releasably lock the swivels 10 and 11 with the tongue 19 thereof disposed crosswise of the slot 20 of the plate 13 or the bracket 17, and 20 to secure to, and centralize the bail 27 with, the body portion 25 of the respective swivel, a resilient member 32 is provided, which is disposed in an axially directed groove 33 formed in the body 25. The groove 33 extends lengthwise through 25 the body 25 at one side thereof and is adapted to be disposed in communication with one of the slot extensions 22 when the respective swivel is in its assembled position, with the plate 13 or bracket 17, as shown in Figure 6. The resilient member 30 32 is herein shown formed of a flat spring metal strip extending from one side and at the top of the body 25, across the same to the other side, and is then bent as at 34, and extends downwardly and toward the first side adjacent the 35 bottom of the body 25. Adjacent the bottom of the body 25, the member 32 is bent to form a loop 36, and is then extended upwardly and outwardly beyond the first side of the body 25, and has its end formed into a finger engaging circular loop 40 36.

The end 37 of the resilient member 32, adjacent the top of the body 25, is provided with transversely extending ears 38 and 39 which are disposed in an annular groove 40 formed in the periphery of the body 25, closely adjacent its top surface. The material of the body 25 is crimped tightly down upon the ears 38 and 39, disposed in the groove 40, to close the groove and clamp the ears therein. The portion 41 of the member 32, 55 which extends downwardly and toward the first side of the body 25, crosses the bore 30 and is thereby disposed between the opposed spaced apart ends 28 and 29 of the bail 27, preventing its transverse movement in respect to the body 25. 60 The looped portion 35 of the member 32 is adapt-

ed to snap into the slot extension 22, to locate, and to indicate that, the tongue 19 is disposed crosswise of the slot 20 in position to hold the swivel to the plate 13 or bracket 17, and to releasably lock the respective swivel in its operative 5 position and against being turned in respect to the plate or bracket. By pressing upwardly upon the finger loop 36, the loop 35 may be removed from the slot extension 22 and the swivel may be turned to align the tongue 19 with the slot 20, 10 whereby the swivel may be removed from its supporting member, herein constituted by the plate 13 or bracket 17, as shown in dotted lines in Figure 6.

In using the device of this invention in association with a gun, the sling strap swivel 11 is connected to the bracket 17, previously secured to the stock 16 by screws 18, as above described. The length of the strap desired is determined and the swivel 10 is connected to the plate 13, previously secured to the stock 16 by screws 14, by inserting its tongue 19 into the desired one of the spaced apart slots 20. Whenever it is desired to alter the degree of looseness of the strap or to shorten its effective length to permit the gun to be more comfortably positioned or balanced and efficiently used, the swivel 10 may be quickly released from the plate 13 and be disposed in the desired position relatively to the gun by inserting its tongue 19 selectively into any one of the slots 20, where- 30 in it will be locked by the spring or resilient member 32 after it has been turned crosswise of the slot by rotation of the swivel. The provision of the member 32 in a device of this nature by which the sling strap swivels may be located and securely locked to their respective supporting or gun connecting members, and which also serves as a bail position retaining element, simplifies the manufacture of such a device and reduces the initial cost thereof, while retaining its efficiency 35 and durability.

It will be understood that the invention may be embodied in other specific forms without departing from the spirit or essential attributes thereof, and it is therefore desired that the present embodiment be considered in all respects as illustrative and not restrictive, and it will be further understood that each and every novel feature and combination thereof present in, or possessed by, the device herein disclosed, forms a part of the invention included in this application.

What is claimed as new and for which it is desired to secure Letters Patent, is:

1. In a sling strap connecting device, a sling strap swivel having a body portion, a strap supporting bail having its ends spaced apart in opposed relation within said body portion, said body portion having a tongue adapted to enter an opening in a gun part, and common means extending across the body portion between the spaced apart bail ends to releasably retain said tongue in the opening in the gun part and to prevent transverse movement of said bail relatively to said body portion.

2. In a sling strap connecting device, a sling strap swivel having a body portion, a strap supporting bail having its ends spaced apart in opposed relation within said body, said body having a tongue adapted to be inserted in an opening in a gun part and be turned into a locked position therein by rotation of said swivel, and common means to enter the opening in a gun part when said tongue is in locked position therein, to releasably retain said swivel against rotation, and extending across the body portion between the

spaced apart bail ends to prevent transverse movement thereof in respect to said body portion.

3. In a sling strap connecting device, a swivel part having an elongated tongue adapted to pass through an elongated opening in a plate and be rotated to dispose it across the opening to lock said swivel to said plate, said swivel part having a slot provided therein adapted to communicate with the opening in said plate when said tongue is in locked position, and a catch secured to said swivel part and disposed in said slot therein and adapted to enter the opening in said plate and releasably lock said swivel against rotation.

15 4. In a sling strap connecting device, a swivel part having an elongated tongue adapted to pass through an elongated opening in a plate and be rotated to dispose it across the opening to lock said swivel to said plate, said swivel part having a slot provided therein adapted to communicate with the opening in said plate when said tongue is in locked position, a bail having its opposed ends disposed in said swivel part and terminating at the slot therein, and a catch member secured to said swivel part and being disposed in the slot therein and between the opposed ends of said bail, said catch being adapted to enter the opening in said plate and releasably lock said swivel against rotation.

30 5. In a device for connecting a sling strap to an article to be carried thereby, a swivel part having a tongue adapted to enter an opening in a part of said article and be rotated into a locked position, said swivel having a slot adapted to be positioned in alignment with the opening in said part of the article when the swivel is disposed in locked position, a strap holding bail having its ends opposed and terminating at opposite sides of the slot in said swivel, and a spring catch member disposed in the slot and extending across between the opposed bail ends, said catch member being adapted to enter the opening in said article part to releasably lock said tongue in locked position.

45 6. In a sling strap swivel, a tongue adapted to enter an opening in a supporting member and be rotated into a locked position, a strap holding bail having its ends spaced apart into opposed relation, and a spring catch extending between and across the opposed ends of said bail and being adapted to enter the opening in said support-

ing member to rotatively lock the tongue in respect thereto.

7. Means to lock a sling strap swivel having an axially directed slot therein and a depending portion to a supporting member having an opening therein to receive the depending portion of said swivel, and to centralize a bail to said swivel including a spring catch disposed in the slot in said swivel and extending between opposed spaced apart ends of the bail, said catch having a portion adapted to snap into the opening in said supporting member to prevent relative rotation between said member and said swivel.

15 8. In a sling strap swivel, a body portion having means to connect it to a supporting member, a bail to hold a strap and having its ends entering said body portion from opposite sides and being spaced apart within said body portion, and a spring catch adapted to prevent relative rotation between said swivel and said member and being disposed between the spaced apart bail ends to prevent lengthwise movement of the same in said body portion.

25 9. In a sling strap connecting device, a sling strap swivel having a tongue adapted to pass through an elongated opening in a gun part and be rotated into a locked position crosswise of said opening, and resilient catch means carried by and rotatable with said swivel to be aligned with the opening in the gun part when the swivel is rotated into locked position and to snap into the aforesaid opening in the gun part when so positioned to lock the swivel against rotation, and a part on said catch means extending from said swivel to be engaged to remove said catch means from the aforesaid opening in the gun part and release said swivel from its locking action.

30 10. In a sling strap swivel, a body portion having means to connect it to a supporting member, a bail to hold a strap and having its ends entering said body portion from opposite sides and being spaced apart within said body portion, and a resilient member within said body portion, said member having a first part disposed between the spaced apart ends of said bail to prevent lengthwise movement of the bail in said body portion, said resilient member having a second part extending out of said body portion, operably connected to said first part to move it out of its position between the ends of said bail.

40 45 50 OSCAR F. MOSSBERG.
